UNITED STATES PATENT OFFICE.

CHARLES D. BROWN, OF MINNEAPOLIS, MINNESOTA, ASSIGNOR OF ONE-HALF TO
GEORGE H. RICHARDS, OF MINNEAPOLIS, MINNESOTA.

SAFE AND VAULT PROTECTING MEANS.

Application filed November 17, 1923. Serial No. 675,326.

The modern burglar's method of breaking into a safe where because of a tight-fitting door, it is impracticable to use an explosive for blowing the door off its hinges, comprises 5 the use of an acetylene cutting torch by means of which a small hole is easily and quickly cut through the wall of the safe and then enlarged by the same means until it is of sufficient size to allow the insertion of 10 the hand and the removal of the money and securities from the safe chamber. No known metal or alloy can withstand the intense heat of the cutting torch and it is only a question of time when the safe breaker 15 can cut through a steel wall of any ordinary thickness and have access to the contents of the safe. Reinforced concrete walls are no protection, as concrete when subjected to the extreme heat of the cutting torch and 20 then instantly cooled by throwing water thereon will immediately dissolve or disintegrate and can be removed with the fingers, and any reinforcing wires or rods therein can of course be instantly cut by the application of the torch. This applies particularly to safes or vaults used in the banks of 25 small towns where comparatively small safes of the portable type are generally used and the elaborate systems of protection employed 30 in the city banks is too expensive to be considered.

The object, therefore, of my present invention is to provide means for protecting safes and vaults from burglars using a cutting torch.

The invention consists generally in various constructions and combinations all as hereinafter described and particularly pointed out in the claims.

40 In the accompanying drawings forming part of this specification,

Figure 1 is a view of a small type of safe with my invention applied thereto, the wall of the safe being shown in section;

45 Figure 2 is a similar view taken on the section line 2-2 of Figure 1;

Figure 3 is a view on line 3-3 of Figure 4, and corresponding to Figure 1, showing the invention adapted for use in a safe that 50 is already built;

Figure 4 is a sectional view on the line 4-4 of Figure 3;

Figure 5 is a perspective view of one section of the rear lining of Figure 3; and

Figure 6 is a perspective view of one section of the wall lining of Figure 3.

In the drawing, 2 represents the walls of the safe having a suitable base 3 and door 4 all of ordinary construction. 5 is the safe chamber having the usual shelf 6 whereon money and other securities may be placed.

In the manufacture of the safe, in the casting of the walls thereof, I provide a hollow chamber 7 extending around the rear and sides of the chamber 5 and provided with a filling opening 8 extending through the wall of the safe. This chamber 7 is filled with a volatile liquid such as ammonia, formaldehyde or some material in suitable form which when released, as by the puncture of the wall of the gas chamber, with a cutting torch will throw off penetrating fumes or a gas and extinguish the flame of the cutting torch, the gas entirely preventing the burning of the torch and the consequent enlargement of the hole sufficiently to permit the robber to insert his hand. The contents of the gas chamber may be of such a nature that a gas will be thrown off so deadly in its effects that no person could stand or work around the safe when the chamber has once been opened and the gas allowed to escape. This discharge will take place the instant the torch has cut its way through the outer wall of the safe and entered the gas chamber and it will thereafter be impossible to use the torch for the purpose of enlarging the hole until the gas chamber has been entirely emptied and the gas dissipated, and this of course will take 90 so long a time that the robber would have no opportunity to complete the wrecking of the safe. After the gas chamber is filled, the filling opening is thoroughly sealed and the outer surface of the safe refinished so 95 that it will be impossible to tell where the filling opening was located.

In the case of a safe already built, I prefer to provide a lining for the money chamber enclosing the back and the walls of the 100 chamber. This lining consists preferably of a series of hollow metallic sections, there being preferably two of these sections above the shelf 6 at the rear triangular in form and fitting against the rear wall and designated by reference numerals 9; these sections having chambers 10 therein wherein the gas or other agent is confined. Below the shelf,

similar sections 11 are provided fitting against the rear wall and resting on the bottom of the money chamber. Around the top and side walls, sections 12 are provided, being curved to fit the curved walls of the safe and preferably the chambers 13 therein are of greater capacity at the top and decrease in area toward the bottom for the purpose of increasing the gas-containing character of the chambers without materially reducing the area of the space wherein the money and securities are kept. Below the shelf, similar curved sections 14 are provided having chambers 15 adapted to contain gas or other substance which will be liberated instantly when the wall of the chamber is perforated. The rear lining sections will be held against forward movement by the wall sections and when the shelf 6 has been put in place, the wall sections cannot drop down until the shelf has been removed and thus the gas containers will completely encircle the money chamber at the rear and all around the sides and form an effectual protection against the use of a cutting torch.

I have shown this invention applied to the wall of a safe but do not confine myself to such use as obviously the same idea may be embodied in the walls of a vault or as a lining for the interior thereof to prevent the use of a torch or other means for cutting a hole through the steel-protecting walls.

The chamber in the wall of the safe may be made in various ways and different forms of lining may be employed and still be within the scope of my invention.

In constructing the walls of a vault, a recess or space may be formed around the room or chamber in the vault and filled with a liquid or gas and hermetically sealed as in the case of a safe. Then when the walls of the vault are penetrated by a torch, the liquid or gas will be liberated and will either extinguish the torch and prevent its further use or throw off such deadly fumes that the robbers cannot continue the vault-breaking operation. In case of vaults already constructed, the room or space therein may be lined with suitable gas or liquid containers and the same protection afforded as shown and described with reference to the safe.

I claim as my invention:

1. The combination with a safe having a chamber therein and a shelf fitting horizontally within said chamber, of rear wall sections in the rear of said chamber above and below said shelf, side wall sections fitting the top, side walls and bottom of said chamber, and seated against said rear wall sections, said sections providing chambers there-

in adapted to contain a gas and said sections being in position to be perforated by the action of a cutting flame penetrating the walls of said safe.

2. A safe having a chamber for valuables and a lining for said chamber composed of separable abutting differently configurated hollow sections arranged in mutually self-sustaining position, and containing a noxious substance adapted to prevent access to the chamber.

3. A safe having a valuables chamber, a lining for said chamber composed of two sets of hollow segmental elements arranged at angles to one another, the elements of each set abuttingly disposed and positionally self-sustaining, one of the sets acting as a lateral support to retain the other.

4. A safe having a valuables chamber, a lining for said chamber composed of two sets of hollow segmental elements adapted to contain a noxious substance, and arranged at angles to one another, the elements of each set abuttingly disposed and positionally self-sustaining, one of the sets acting as a lateral support and retainer for the other, and a shelf interposed between the elements of both sets, and supported by and supporting said elements.

5. A safe having a valuables chamber, a lining for said chamber composed of differentially configurated sets of hollow segmental elements adapted to contain a noxious substance arranged both in coplanar relation, and at angles to one another, said elements being adapted to distribute a noxious gas when punctured or broken.

6. A safe having a cylindrical valuables chamber and a door opening concentric with the axis of said chamber, a lining for said chamber comprising two sets of hollow elements each adapted to contain a noxious substance, one comprising cylindrical segments and the other flat circular segments, the segmental elements of each set being self-sustainingly abuttingly disposed, with the elements of one set abutting those of the other for securing that set against lateral collapse.

7. A safe having a chamber for valuables and a lining for said chamber composed of differently configurated sets of hollow abutting sections self-sustainingly arranged, and each having a noxious substance therein, adapted to prevent access through the safe walls for the removal of valuables in said chamber.

In witness whereof, I have hereunto set my hand this 14th day of November 1923.

CHARLES D. BROWN.
